ATTORNEY

UNITED STATES PATENT OFFICE.

WILLIAM F. BRUNING, OF NEW YORK, N. Y.

COCKTAIL-SHAKER TOP.

Application filed April 11, 1928. Serial No. 269,171.

This invention relates to caps for shakers, and particularly to an improved cap for a cocktail or other beverage shaker, the object being to provide a comparatively simple 5 form of cap, and one which will function properly as a stopper, as a strainer and as means presenting a pouring spout.

Another object of the invention is to provide a cap or closure for beverage shakers, 10 wherein oppositely extending spouts are provided with a strainer connected therewith to prevent ice and other material from moving out with the liquid.

A further object, more specifically, is to 15 provide a cap or closure for cocktail shakers, wherein a strainer is provided and acts as a clamping member for holding the cork stopper structure firmly in position at all times.

20 An additional object is to provide a cap for cocktail shakers, wherein the device as a whole presents a closure for the shaker and means are provided and forming part of the cap which will convert the cap into 25 a discharge member.

In the accompanying drawing,—

Figure 1 is a top plan view of a cap disclosing an embodiment of the invention, the same being shown applied to a container or 30 shaker;

Figure 2 is a side view of the cap shown in Figure 1, part of a container being shown in connection therewith;

Figure 3 is a sectional view through Figure 1, approximately on the line 3—3;

Figure 4 is a bottom plan view of the strainer shown in Figure 3, the same being on a reduced scale.

Referring to the accompanying drawing 40 by numerals, 1 indicates a container or shaker provided with a mouth 2. This container may be made of glass or any desired material of any desired size. In shakers for cocktails or for other beverages some 45 kind of a stopper must be provided, and the present invention refers to a suitable cap or closure for the shaker or container 1.

As shown particularly in Figure 3, the cap embodying the invention is provided 50 with what may be termed a body 3 merging into pouring spouts 4 and 5 and also merging into an apron 6 and a threaded tubular extension 7. The body 3 is provided with an opening substantially in line with the extension 7 whereby the auxiliary closure or 55 stopper 8 may be positioned in body 3. This

closure is provided with a cork member 9 held in place against the lower part of knob 10 by a screw 11 threaded into an extension 12 of knob 10. By removing the auxiliary closure 8 liquid from the shaker 1 could be poured readily into a receptacle without removing the cap. A closure member of cork 13 is pressed against the under-side of apron 6 by the flaring portion 14 of the screen or strainer 15. It will be noted that the strainer 15 is provided with a foraminous plate 16 soldered, welded or otherwise secured to the flange 17 which merges into the tapering portion or section 14. This tapering portion 70 merges into an externally-threaded tubular portion 18 adapted to be screwed into extension 7 for holding the strainer in place and also for causing the strainer to clamp the cork 3 in place. This cork is made of 75 a size to properly fit the mouth 2 and is preferably somewhat tapering so that a tight fit may be secured, while the downward deflection in the apron is to enable the apron to slip over the edge of the glass container and thus conceal the area of cork 80 which would otherwise show above the rim of the vessel. In operation when it is desired to prepare a cocktail or other beverage, the body 3 is grasped and the entire 85 cap is removed. The ingredients are then placed in the shaker and the cap re-applied and forced down into the neck 2 until tight, as shown in Figures 2 and 3. The shaker may then be agitated or shaken to any desired extent and when it is desired to pour 90 some of the liquid from the shaker, the auxiliary closure 8 is removed and the shaker tilted so that the tapering portion 14, body 3 and one of the spouts 4 and 5 will act as 95 a pouring outlet structure.

What I claim is:—

1. A cap for a cocktail shaker, comprising a tubular body merging at one end into a pair of pouring spouts and at the other end into a covering apron and an internally-threaded sleeve, a cork member arranged beneath said apron, and a strainer formed with a conical shaped portion fitting against said cork for holding the same in position 100 and against said apron, said strainer being provided with a foraminous plate at one end and an externally-threaded tubular portion at the other end, said externally threaded tubular portion being adapted to be screwed 105 into said sleeve.

2. A cap for cocktail shakers, comprising

a closure structure having a discharge opening merging into a pair of oppositely extending spouts formed substantially arc-shaped on their exteriors both longitudinally 5 and transversely so as to act in the capacity of handles, and an auxiliary closure mounted in the opening of the first-mentioned closure for closing the opening.

3. A cap, comprising a cork ring having 10 a tapering passageway therethrough, a cap body having a tubular outlet and an apron overlapping part of said cork ring, a strainer removably secured to said body, said strainer having a tapering portion fitting into said 15 passageway for clamping said ring against said apron, and an auxiliary closure for normally closing the opening in said body.

4. A cap for containers, comprising a packing ring having a tapering aperture 20 extending therethrough, a body having a portion acting as an abutment for said ring, a strainer removably connected with said body and formed with a tapering portion

fitting into said tapering passageway, said tapering portion acting to clamp the packing ring in said abutment, said body having a discharge opening merging into a discharge spout, and a removable stopper for said discharge opening.

5. In a cap for containers, a body formed 30 with an apron and a tubular internally-threaded portion, a packing member fitted against said apron and a strainer structure adapted to clamp the packing member against the apron, said strainer structure including a foraminous plate, a conical-shaped section and an exteriorly-threaded tubular section positioned so that the threaded portion of the strainers will be fitted into the threaded portion of the body for causing 40 the conical-shaped section to clamp the packing member against said apron.

Signed at New York, in the county of New York and State of New York this seventh day of April, A. D. 1928.

WILLIAM F. BRUNING.
